UNITED STATES PATENT OFFICE.

ALBRECHT SCHMIDT, OF HÖCHST-ON-THE-MAIN, GERMANY, ASSIGNOR TO FARBWERKE VORM. MEISTER LUCIUS & BRUNING, OF HÖCHST-ON-THE-MAIN, GERMANY, A CORPORATION OF GERMANY.

MANUFACTURE OF INDIGO-WHITE PREPARATIONS SUITABLE FOR FERMENTATION-VATS.

No. 906,307.

Specification of Letters Patent.

Patented Dec. 8, 1908.

Application filed March 22, 1905. Serial No. 251,447.

To all whom it may concern:

Be it known that I, ALBRECHT SCHMIDT, Ph. D., chemist, a citizen of the Empire of Germany, and residing at Höchst-on-the-5 Main, Germany, have invented certain new and useful Improvements in the Manufacture of Indigo-White Preparations Suitable for Vats, Especially Fermentation-Vats, of which the following is a specification.

10 A considerable part of indigo is used for the fermentation-vat, especially in Eastern countries. The chemical vats require the indigo to be in a fine state of sub-division and capable of being readily made into a 15 paste, a condition all the more essential for the fermentation-vat. The reason why synthetic indigo has hitherto not been able to supplant natural indigo is that the latter is readily soluble in the fermentation-vat, 20 yielding excellent vats, whereas the conversion of synthetic indigo into a soluble vat meets with greater difficulties. This disadvantage of the synthetic indigo is due to the 25 physical condition of the products in question, which may be explained by the various methods of their preparation. Natural indigo is isolated at its place of production as a fine amorphous powder from the glucosid of strongly diluted indigo-white. Its particles 30 are so fine as to resist only slightly the reducing action of agents in the vat and thus are readily dissolved.

Synthetic indigo is obtained from comparatively very concentrated solutions of indoxyl by oxidation and condensation; under 35 these circumstances synthetic indigo is produced in crystalline form. As a consequence of its physical structure, the synthetic indigo greatly resists the gentle reducing agents of 40 the vat, so that the artificial product dissolves only insufficiently in the different fermentation-vats. From a commercial point an essential difference has to be made between natural and synthetic indigo. As 45 soon as this difference was recognized by the producers, efforts were made to bring the synthetic indigo into such a form as to permit its being used in the fermentation-vat.

It has been tried to obtain synthetic indigo in a finely divided state by grinding indigo powder in the disintegrator, without, 50 however, attaining the desired state of fine subdivision of natural indigo. The pastes

prepared by the consumer in grinding indigo powder in a moist condition did not come 55 near to the reducibility of natural indigo. Nor was the object attained by means of the known process of treating indigo with sulfuric acid. Further experiments were made to treat indigo cakes similar to alizarin 60 cakes, with starch, dextrin etc. These indigo-lumps, however, could not supersede the natural indigo in the fermentation-vats. Another method to obtain a suitable product was to mix indigo pastes with ferments and 65 alkalies, yet with no better result. None of these methods succeeded in giving to the synthetic indigo such a form as to permit a competition with the natural indigo.

The best preparation hitherto obtained is 70 that in form of a paste of 20%. It has supplanted natural indigo in all chemical vats, but for the fermentation-vat, especially in the East, it is not that what is wanted. Apart from the little reducibility, the pasty form is 75 rather inconvenient for transport and little suitable for the small consumer of the East, for as soon as the packages are opened the paste soon becomes dry and very difficult to reduce afterwards. Applicant has tried an 80 other way to overcome these difficulties and succeeded in obtaining a highly concentrated indigo-preparation more suited for the fermentation-vat than natural indigo. This process consists in mixing indigo-white with 85 molasses, syrup and similar bodies. The difficulties to overcome were to obtain a vat preparation having the following characteristics:

1. The vat or indigo-white composition had 90 to be highly concentrated for reasons of transport and at the same time capable of being made into a paste.

2. Stability towards the oxidizing action of the air, permitting even the use of not 95 quite air-tight barrels.

3. The composition should not be influenced by the warm atmosphere of the East, even after the barrel or like packing has been opened, that is to say, the preparation must 100 at any time be capable of being made into a paste containing the indigo in form of indigo-white capable of reaction.

It is clear that from the outset there was little hope to find such a preparation answering 105 all these requirements. In fact, the first

attempts failed. Thus, for instance, it was difficult to obtain a stable indigo-white, whereby it was noticed that even press-cakes soon turned into indigo when exposed to air.

5 An attempt to air-tight packing indigo-white press-cakes was not successful, owing to the cost and also to the indigo-white becoming indigo when the packages were exposed to air; the contents decomposed into

10 crystalline indigo-white and water. The difficulties experienced are best shown by the fact that thin vat preparations have been in use for a long time, even before synthetic indigo was known, but a concentrated indigo-

15 white preparation has never been known on the market. Other attempts were made to give to indigo-white a concentrated, stable form, by producing formaldehyde-indigo-white, carbonic acid ester-indigo-white, acetic acid ester-indigo-white etc., yet all these methods were by far too expensive and useless for the fermentation-vat, as these compounds had first to undergo an isolating process.

20 25 Now, while preparing a fermentation-vat with indigo-white instead of indigo, in presence of molasses as organic nutrient, indigo-white press cakes stirred with water were mixed and this mixture was added to the fermentation-vat. It was observed that the dried-up parts, instead of becoming blue by the oxidation of the air, were left intact. The addition of molasses evidently had a peculiarly preserving influence on the indigo-

30 35 white, as was proved afterwards by further experiments. An experiment based on this observation for obtaining a commercial product by mixing molasses and indigo-white met with no success in another direction, for

40 it is shown, that mixtures of indigo with organic bodies, such as starch, dextrin etc. soon become moldy. Compare British patent No. 3108/04, lines 6-13. The addition of alkali hydrate or lime as given in this patent

45 is only of momentary advantage, as by allowing the indigo-white product to stand, the alkali disappears and the mass begins to mold and ferment. By further tests it was found that by impregnating indigo-white

50 sufficiently with concentrated molasses, products may be obtained which are not only stable towards the influence of the air, but also towards mold and fermentation. The reason for this was found in the fact that

55 technical indigo-white, brominated indigo-white, tolyl-indigo-white etc., contrary to indigo, possess slightly antiseptic properties and that molasses, especially when highly concentrated, have a preservative action as a

60 consequence of their containing sugar and considerable proportions of salts. It is thus possible to obtain pastes containing 30, 40, 50 and more per cent. of indigo-white, which may be simply packed in casks, where they

65 remain intact, even when parts of the con-

tents have been used. It is remarkable that these products may be readily made into pastes without becoming dry, which is due to the large proportion of hygroscopic salts and liquefiable substances contained therein. 70 The contents of water of the products may even be reduced so far as to obtain no longer pastes but solid bodies, such as lumps, powder etc. and yet these products are still capable of being made into pastes without losing 75 their favorable properties.

Stable indigo-white preparations may be obtained in different ways, according to the degree of consistency of the product desired. For instance, indigo-white press-cakes may 80 be directly mixed with molasses or syrup, part of the water being distilled off in a suitable apparatus, such as in a vacuum, until the desired product is obtained, either as a paste, or in a semi-solid or solid form. Or the moist 85 indigo-white, pressed hydraulically, may be mixed in the kneading machine with molasses, until a handy paste is obtained, or again, indigo-white press cakes are washed out with molasses and the product thus obtained is 90 stirred alone or with a further quantity of molasses. The proportions of indigo-white and molasses vary according to the product desired; though, in general, it is not of advantage to allow the quantity of water in the 95 molasses to be too great, as in case of too strong a dilution, the product is more liable to become moldy. The new products form concentrated, stable, indigo-white preparations which are soluble in dilute soda-lye 100 with a yellow-green solution from which, when exposed to the air, blue flakes will separate, partly soluble in water, the insoluble part being soluble in soda-lye, while the part soluble in water shows the known reaction of 105 saccharides.

Example I. 1000 parts of indigo-white (containing about 75 per cent. of dry indigo) obtained by means of zinc, bisulfite, hydro-sulfite, or electrolysis and hydraulically 110 pressed at about 200 atmospheres in the kneading machine, are stirred with, for instance, 700 or about 400 parts of thickly liquid molasses or any sugar syrup, cane sugar, invert sugar, maltose, glucose, maltose or other saccharine substance, further dehydrated if necessary. The pasty product may be used at once.

Example II. The process is the same as in Example I, only for the hydraulically pressed 120 indigo-white, indigo-white paste is used, by mixing 280 kil. of press-cakes (= 80 parts of indigo-white) with, for instance, 100, 80 or 50 parts of molasses or sugar syrup, cane sugar, invert sugar, glucose, or other saccharine substance, such, for instance, as milk sugar, preferably in presence of other sugars 125 readily soluble in water, from which about 100-170 parts of water are distilled off in a vacuum, so that after evaporating, a pasty 130

or if further distilled, a solid product is finally obtained.

The process described for obtaining indigo-white from indigo may also be applied 5 to other indigo-white derivatives (substitution products), such, for instance, as indigo-white from methyl-indigo, (tolyl-indigo), especially ortho-tolyl-indigo or as halogen-indigo-whites, for instance, brominated, di-10 brominated and chlorinated indigo.

Having now described my invention, what I claim is:

1. The process herein described of making concentrated, stable, indigo-white preparations especially suited for fermentation-vats, which consists in incorporating indigo-whites 15 with saccharine substances.

2. As new products, concentrated, stable,

indigo-white preparations especially suited for fermentation-vats, obtained by incorporating indigo-whites with saccharine substances, said products being soluble in dilute soda-lye with a yellow-green solution from which, when exposed to the air, blue flakes will separate, partly soluble in water, where- 20 by the insoluble part is soluble in soda-lye, and the part soluble in water shows the known reaction of saccharides. 25

In testimony that I claim the foregoing as my invention, I have signed my name in presence of two subscribing witnesses.

ALBRECHT SCHMIDT.
